MULTIBREAK GAS BLAST CIRCUIT
BREAKER WITH GROUNDED OPER-
ATING MOTORGustav E. Jansson, North Quincy, Mass., assignor

Milwaukee, Wis., a corporation of Delaware

Application July 19, 1947, Serial No. 762,092

12 Claims. (Cl. 200—148)

1

My invention relates to electric circuit breakers of the gas or fluid blast type adaptable for very high voltage ratings, particularly to air blast circuit breakers, and it has for its principal object the provision of improved multibreak structure for effecting synchronous operation of the contacts at all breaks pertaining to one pole of the circuit breaker or one phase of the circuit.

Another object of my present invention is to provide an improved gas blast circuit breaker comprising a plurality of pairs of cooperating arcing contacts arranged in electrical and spatial series relation in one pole unit of the circuit breaker structure and means for compelling, at a point of time at which a predetermined minimum amount of gas pressure prevails at all points of break, simultaneous positive-action separation of all cooperating pairs of arcing contacts.

Another object of my present invention is to provide a gas blast circuit breaker of the type comprising a plurality of pairs of cooperating arcing contacts arranged in electrical and spatial series relation in one pole unit of the circuit breaker structure, wherein all said pairs of contacts may be separated simultaneously independently of the gas pressure at different points of break, and irrespective of whether there is a difference in gas pressure at different points of break.

Another object of the present invention is to provide a gas blast circuit breaker of the type comprising a vertical hollow insulating column accommodating therein a plurality of superimposed pairs of cooperating arcing contacts arranged in electrical series relation and which includes motor means arranged at ground potential and adapted to separate simultaneously said plurality of pairs of contacts, and which includes, in addition thereto, time delay means for causing operation of said motor means after a time delay following the opening of the blast valve of the circuit breaker sufficient to permit substantial equalization of the pressure at all points of break.

Another object of my present invention is to provide a gas blast circuit breaker pole unit including one movable arcing contact, or a plurality of movable arcing contacts arranged in electrical series relation, which contact is or contacts are adapted to be operated through the intermediary of rotating insulating structure by means of a single motor arranged at ground potential remote from said contact or contacts.

Another object of the present invention is to provide an improved circuit breaker structure of the gas blast type which lends itself to the inter-

2

ruption of circuits having a very high operating voltage, is simple, reliable in operation and relatively inexpensive to manufacture.

Objects and advantages other than those described above will be apparent from the following description when read in connection with the accompanying drawing, in which:

Fig. 1 is a pressure vs. time characteristic for a fluid passage having a given geometrical configuration;

Fig. 2 is a diagrammatical view, partly in cross section and partly in side elevation, of a gas blast multibreak circuit breaker of the outdoor type embodying the features of the present invention;

Fig. 3 is a view, partly in cross section and partly in side elevation, of the circuit breaker column and operating mechanism of Fig. 2, shown on a larger scale;

Fig. 4 is a cross section taken along line IV—IV of Fig. 3, seen in the direction of the arrows indicated in Fig. 3;

Fig. 5 is a cross section taken along line V—V of Fig. 3, seen in the direction of the arrows indicated in Fig. 3;

Fig. 6 is a front view, partly in cross section and partly in side elevation, of a modification of the contact operating mechanism of Fig. 3;

Fig. 7 is a cross section taken along line VII—VII of Fig. 6, seen in the direction of the arrows indicated in Fig. 6; and

Fig. 8 is a diagrammatic view, partly in cross section and partly in side elevation, of an operating mechanism intended to be used in combination with the circuit breaker structure of Figs. 2 and 3 for the purpose of rapid reclosing service.

A multibreak gas blast circuit breaker comprises means defining a blast passage having at one end thereof a blast valve for the admission therein of gas under pressure. A plurality of breaks is arranged within the passage at different points along the axis thereof. Since it takes time for the blast or pressure wave to develop and to rush or travel through the blast passage, shortly upon opening of the blast valve the pressure within the blast passage will differ depending both upon the particular point of time under consideration as well as upon the location of any particular point under consideration along the axis of the blast passage. Owing to these facts there will be a tendency in a multibreak gas blast circuit breaker that opening of cooperating pairs of fluid pressure operated contacts occurs at different points of time, depending on how far such pairs of contacts are arranged away from the blast-admitting valve. In addition thereto, there

55

will be a tendency that the intensity of the arc extinguishing blast will vary depending upon the location within the blast passage of a particular pair of cooperating contacts, and upon the point of time at which the particular pair of contacts under consideration is permitted to part. Fig. 1 shows the pressure vs. time characteristic for the end of an 11 ft. long pipe line having restricted outlet and intake areas, the fixed ratio of which is 0 (outlet closed), and .445, respectively (outlet open). It appears from Fig. 1 that the pressure wave rises gradually with time to a peak value and then decreases in form of a relatively slightly damped oscillation if the outlet is closed, and in the form of a very strongly damped almost aperiodic oscillation in case the outlet is open.

The foregoing shows that it is of great importance to provide gas blast multibreak circuit breakers with means which permit to synchronize the operation of all the contacts and which, in addition thereto, permit proper timing between the opening of the blast valve, the transit of a given pressure wave and the separation of the contacts so as to permit building-up of the right amount of gas pressure within the blast passage at any point thereof where a pair of cooperating contacts is located.

This problem has been solved by the structure which is shown in Figs. 2 and 3, and which will now be described in detail.

Breaker tank 1 constitutes a source of fluid, e. g., air, under pressure for producing arc extinguishing blasts of gas as well as for operating the contacts of the circuit breaker. Pipe 2 supplies gas under pressure to tank 1 either from another larger tank or from a compressor, of which neither are shown in the drawing. Blast valve 3a controls the escape of gas under pressure into blast passage 3. The circuit breaker comprises further a plurality of pairs of cooperating arcing contacts 4, 5 arranged in electrical and spatial series relation or registry within blast passage 3. Contacts 4 are stationary and tubular, or of the nozzle type, and contacts 5 are movable and of the plug type, normally closing the orifices formed by the nozzle type contacts. Upon separation of each pair of cooperating contacts 4, 5 an arc extinguishing blast of gas under pressure is caused to rush through the gaps which are formed therebetween. These blasts of gas have been indicated by arrows in Figs. 2 and 3. The structure which causes these blasts of gas to form will be described below more in detail. Separation of cooperating pairs of contacts 4, 5 is effected by a fluid motor generally indicated by the reference sign 6, a crank mechanism 7, a rotatable insulating column generally indicated by the reference sign 8, two crank mechanisms 9, both associated with column 8, and contact operating linkages including the reciprocable operating rods 10. Gas under pressure is applied to motor 6 comprising relatively movable cylinder 12 and piston 13 from blast passage 3 through pipe 11 which branches off blast passage 3 at a point situated downstream with regard to blast valve 3a. Upon a predetermined movement of piston 13 in cylinder 12 in contact opening direction, port 14 is freed by piston 13, thus permitting pipe 15 to be supplied with gas under pressure. Gas under pressure flowing through pipe 15 causes a fluid motor which has been generally indicated by reference sign 16 to open a disconnect switch which has been generally indicated by reference sign 17. Fluid motor 16 comprises relatively movable piston 18 and cylinder 19 and

a slide valve 20. The flow of gas under pressure supplied through pipe 15 causes both piston 18 and slide valve 20 to move from right to left. The movement of slide valve 20 to the left causes opening of port area 21, thus permitting venting of the left side of cylinder 19 to atmosphere. Disconnect switch 17 comprises the stationary contact 22 and the movable or rotatable contact 23. The latter is adapted to be actuated by motor 16 through crank mechanism 24, rotary insulating column 25 and bevel gear 26. The circuit through the circuit breaker when in closed position is as follows: line 27, terminal 28, arcing contacts 4, 5, flexible conductor 29, arcing contacts 5, 4, 4, 5, flexible conductor 29, arcing contacts 5, 4, terminal 30, disconnect contact 23, disconnect contact 22, terminal 31, line 32. Motor 16 for operating disconnect switch 17 is associated with auxiliary switch 33 which is being closed upon a predetermined travel of piston 18 in contact opening direction. Closing of switch 33 causes closing of a control circuit which includes conductor 34 and solenoid contact resetting valve 35. When valve 35 opens, gas under pressure is permitted to flow from tank 1 through pipe 36 to motor 6. This causes piston 13 and slide valve 38 to move from left to right, resulting in closing of cooperating pairs of arcing contacts 4, 5 and venting of the right side of cylinder 12 through port 39. The contact closing action of motor 6 is speeded up by the action of spring 40 which exerts the required contact pressure when the circuit is closed by the arcing contacts 4, 5 of the circuit breaker. In the contemplated case the circuit will not be closed upon resetting of arcing contacts 4, 5 since it is interrupted by reason of separation of disconnect contacts 22, 23.

Operation of the circuit breaker is initiated by energizing solenoid trip valve 41. This permits a flow of gas under pressure from tank 1 through pipe line 43 to pilot valve 44, causing the latter to open. Opening of pilot valve 44 permits gas under pressure to flow from tank 1 in back of piston 45 of a fluid motor 46 for operating blast valve 3a. Motor 46 comprises also cylinder 47 and spring 48 arranged therein for reclosing blast valve 3a and maintaining it in closed position. Upon opening of blast valve 3a cooperating pairs of arcing contacts 4, 5 are opened by motor 6, whereupon disconnect switch 17 is opened by motor 16, and finally contacts 4, 5 are reclosed by the combined action of motor 6 and spring 40, as described above.

Closing of the circuit breaker is initiated by energizing solenoid valve 49, thus causing gas under pressure to flow from tank 1 through pipes 43 and 43a to motor 16. That flow of gas under pressure causes piston 18 and slide valve 20 to move from left to right. This in turn causes contacts 22, 23 to engage and port area 50 to be opened to atmosphere for venting the right side of cylinder 19.

Referring now particularly to Fig. 3, it will be seen from that figure that the blast passage 3 is in part defined by a hollow supporting insulator 51 and also by a plurality of hollow insulating elements 53 which are arranged in registry and are superimposed upon insulator 51. What may be termed the circuit breaker column proper which has generally been designated by reference sign 200, comprises said hollow insulating elements or tubular insulators 53 and a plurality of metal casings 52. Insulators 53 are arranged coaxially on opposite sides of metal casings 52

and form spatial extensions of chambers defined by casings 52. Each insulator 53 houses a pair of cooperating arcing contacts 4, 5 and is provided with a substantially cylindrical element 54. Elements 54 define guiding surfaces 55 for insuring movement of contacts 5 in a straight, preferably a vertical line. Elements 54 are each provided with a flange 56 clamped between one of the casings 52 and one of the insulators 53. This clamping feature holds element 54 firmly in position, thus insuring proper alignment of all the stationary and movable contacts 4, 5. Flanges 56 are provided with apertures 57 (shown in dotted lines in Fig. 3 and more clearly in Fig. 7) for permitting gas under pressure to flow in an upward direction through insulators 53 and metal casings 52 up to the top of the column 200. The stationary contacts 4 are provided with flanges forming part of venting structures which are more fully described below. The flanges which are associated with contacts 4 provide a clamping feature of the same kind as flanges 56 of elements 54.

Operation of contacts 5 is effected by push-pull or reciprocating operating mechanisms, i. e., mechanisms adapted for positive fluid-pressure-action actuation of contacts 5 in alternative directions. Each metal casing 52 houses one push-pull operating mechanism generally indicated by the reference numeral 58. Each push-pull operating mechanism 58 is adapted to convert operating impulses in a direction transversal of passage 3 and tubular insulators 53 into a pair of opposite forces in a direction longitudinal of said passage and insulators. There are many possible operating mechanisms capable of converting transversal operating impulses of operating rods 10 into a pair of opposite operating impulses in a direction longitudinal of circuit breaker column 200, and Fig. 3 shows merely one possible, though a preferred, push-pull operating structure of that kind. Each of the contacts 5 is adapted to be operated by a crank or toggle mechanism comprising the elements 59 and 60. Each pair of elements 59 is rotatable about a common shaft 61 arranged in a direction transversal of the breaker column 200 and supported by one of the metal casings 52. The metal casings 52 are each provided with a slide bearing 62 for supporting operating rods 10. Rods 10 are each connected to a pair of elements 59 by means of a toggle comprising two links 63. Each metal casing 52 has two wide flanges 64 for securing the tubular insulators 53 to it. This is achieved by means of angle members 65, wedge members 66 and screws 67.

The mechanisms 59, 60 described above form toggle joints for transmitting the reciprocating force produced by the movement of operating rods 10 in a direction substantially in alignment with the axis of contacts 4 and 5. Elements 60 and interconnected elements 59 actuate movable contacts 5 upon movement of operating rods 10 and substantially reduce the side thrust which would be exerted by operating rods 10 on movable contacts 5 if only toggles 63 were connected therebetween.

As clearly shown in Fig. 4, the apertures 57 in flange 56 are arranged in such a way as to cause the vertical flow of gas under pressure through casing 52 to bypass the push-pull operating mechanism 58 which is arranged in that casing, thus minimizing frictional losses within said flow of gas under pressure. The lower metal

casing 52 is constructed in the same way as the upper metal casing 52.

The end of each insulator 53 arranged remote from the respective casing 52 to which the insulator is secured is provided with means permitting the escape of arc products or fluid under pressure from tubular contacts 4 to atmosphere. These venting means comprise metal structures generally indicated by reference numeral 201 defining passages 70 for the escape of arc products in a substantially horizontal direction. Cooling structures 202 arranged in passages 70 effect a reduction of the temperature of the escaping arc products prior to their escape. The cooling structures 202 consist preferably of stacks of parallel plates of a metal having a high heat absorbing capacity, e. g., copper, and they are arranged in the direction of the flow of arc products so as to minimize frictional flow losses. The venting structure 201 arranged in the middle of the breaker column 200 comprises a partition plate 71 which may be of insulating material and separates the arc products issuing from immediately adjacent nozzle contacts 4 prior to their cooling and release to atmosphere.

As shown in Fig. 5, the venting structure 201 which is arranged in the middle of the breaker column 200 comprises partitions 72 defining two ducts 73 which permit a direct flow of gas under pressure from the insulator 53 immediately below partition 71 to the insulator 53 immediately above partition 71, thus bypassing venting passages 70. The venting structure 201 on the bottom of the breaker column 200 is constructed in a similar way, i. e., it permits air under pressure issuing from tubular insulator 51 to flow directly into the lowermost insulator 53, thus bypassing the exhaust passages 70 situated at the bottom end of the breaker column 200. The venting structure 201 on top of column 200 permits escape of all the air under pressure which reaches the top of said column, i. e., it has no bypass means as the two venting structures which are arranged at a lower level.

Gas under pressure entering the lowermost insulator 53 may, in part, escape through the gap formed between the lowermost contacts 4, 5 upon separation thereof, and in part rush through apertures 57 in flanges 56 and the lower metal casing 52 into the next higher insulator 53. Here again the flow of gas under pressure is divided into two branch flows, one escaping through the gap formed between contacts 4, 5 upon separation thereof and through the venting passage 70 of the venting structure 201 situated at the middle of column 200, and the other flowing through bypass ducts 73 (see Fig. 5) to the insulator 53 situated immediately above the middle of the breaker column 200. Here the flow of gas under pressure undergoes another subdivision into two branch flows. One branch flow follows the path through the gap formed between the separated contacts 4, 5 and the upper of the venting passages 70 of structure 201 situated at the middle of column 200. The other branch flow follows the path through apertures 57 in flanges 56 and through casing 52 into the uppermost insulator 53, and then through the gap formed between the uppermost contacts 4, 5 upon separation thereof and through the venting passages 70 situated on the top of the circuit breaker column 200 to atmosphere.

The vertical rotary insulating column 8 is made up of two parts 8a and 8b. The lower part 8b is adapted to be rotated by fluid motor 6 which

is arranged at ground potential, or substantially at ground potential. The lower crank mechanism 9 for actuation of one of the operating rods 10 is arranged between the parts 8a, 8b of rotary insulator 8. Shaft 74 interconnects parts 8a and 8b of insulator 8, and that shaft is supported by a bearing 75 which in turn is supported by a rigid cross-tie 76, which is secured to the lower of the two casings 52. The shaft 77 on top of part 8a of rotatable insulator 8 is supported by a bearing 78 which in turn is supported by a rigid cross-tie 79 which is secured to the upper of the two casings 52. It will be noted that both cross-ties 76 and 79 are substantially horizontal and situated at about the same level as metal casings 52, or shafts 61, respectively.

The flexible conductors 29 which have been shown in Fig. 2 have been omitted in Fig. 3, for clearness' sake, but it is to be understood that each pair of movable contacts 5 which is associated with one push-pull operating mechanism 58 is electrically interconnected. Since all arcing contacts 4, 5 of the circuit breaker are supposed to be serially connected when the breaker is in the closed position thereof, it is necessary to provide means for electrically interconnecting the two tubular contacts 4 which are arranged close to the middle of the breaker column 200. This interconnection is effected by the metallic cooling structure 201 (see particularly Fig. 5) and a shunt conductor may be added, if desired, for electrically interconnecting said contacts 4.

It will be noted that the interval of time or time delay between initiation by opening of blast valve 3a of building-up of pressure within the circuit breaker column 200 and simultaneous parting of all pairs of contacts 4, 5 depends upon the operation of fluid motor 6. The point of time at which motor 6 begins to operate depends in turn upon the cross section of pipe 11 and can be varied, if desired, by arranging a needle valve therein (no such valve has been indicated in the drawing).

Since nozzle and plug contacts 4, 5 are separated and gas under pressure is permitted to escape from column 200 only subsequent to the opening of blast valve 3a, column 200 will be substantially closed at the point of time when blast valve 3a is being opened. Hence a damped pressure wave of the character shown in Fig. 1 will occur within column 200 immediately upon opening of blast valve 3a. Contacts 4, 5 are separated at a suitable point of time when the pressure conditions prevailing in breaker column 200 at the various points of break are most favorable for efficient circuit interruption.

In the closed position of contacts 4, 5 the angle between contact operating elements 59 and 60 is close to 180 degrees. Shifting of operating rods 10 from the right to the left, as viewed in Fig. 3, results in rapid reduction of the pressure between contacts 4, 5 to zero and separation of said contacts.

Figs. 2 and 3 show one pole-unit for controlling one phase of an electric circuit. In the case of multiphase circuits, a plurality of such pole-units may be associated for controlling all the phases of the circuit. Storage tank 1 and the blast valve 3a may be common to all pole units of a composite multiphase circuit breaker. This common tank and blast valve feature is less appropriate for relatively large multiphase circuit breaker arrangements; the pole units of relatively large multiphase circuit breaker arrangements should preferably each have a

separate breaker tank and a separate blast valve.

It will be understood that the contact structure and operating means shown in Figs. 2 and 3 are not limited to multibreak circuit breakers but can also be used to advantage in circuit breakers having but one point of break. In gas blast circuit breakers of the multibreak type there is a relatively long distance between the blast valve and the arcing contacts which are arranged most remotely therefrom, and, therefore, the possibility of proper timing of the separation of cooperating pairs of contacts is of paramount importance in the case of multi-break gas blast circuit breakers. Besides, the problem of synchronizing the operation of the contacts of one pole-unit is peculiar to multi-break circuit breakers.

The circuit breaker of the present invention comprises, as has been shown before, a plurality of identical basic structures as, for instance, casings 52, insulators 53, operating mechanisms 58. The number of these basic structural elements can be decreased or increased depending upon the required voltage rating and interrupting capacity rating, i. e., different circuit breakers to suit different requirements can be assembled from the same basic elements.

The reactions of the accelerating forces to which contacts 4, 5 are subjected are of opposite direction; the forces acting upon bearings 75 and 78 tend to move said bearings to the left, while the forces which are transmitted by shafts 61 upon metal casings 52 tend to move said casings to the right, as viewed in Fig. 3. These forces are substantially balanced by the provision of the cross-ties 76 and 79 of which each interconnects one of the bearings 75 and 78 with one of the two metal casings 52, and which are arranged at about the same level as shafts 61. Cross-ties 76 and 79 will be subjected to tensile stresses, but all accelerating forces or their reactions, respectively, are substantially kept away from the insulating elements 53 of which column 200 is made up, which elements are generally of ceramic material, and, therefore, not well adapted to withstand mechanical impact forces.

Another desirable feature of the circuit breaker of the present invention consists in that contacts 4, 5 can be reclosed against full gas pressure in the interrupting chambers formed by insulators 53, which is evidently due to the fact that the operation of fluid motor 6 does not depend upon the pressure within column 200. The gear ratio of the operating mechanism 8, 9, 10 and 58 is such that extremely high contact pressures can be exerted with relatively small forces being present at the motor-end of said mechanism.

Referring now to Figs. 6 and 7, metal casing 52 is situated between a pair of coaxially arranged insulators 53. Insulators 53 rest upon the wide flanges of casing 52 and are secured to them by means including members 65 and 66. Each insulator 53 houses a stationary nozzle contact 4, a movable plug contact 5 and a member 54 defining guiding surfaces for telescoping contacts 4 along a straight line, i. e., the direction of the axis of passage 3. Casing 52 is provided with two bearings 81 and 82 for supporting shaft 83. Shaft 83 carries crank element 84. Crank elements 65 interconnect each of the movable contacts 5 with one of the ends of crank element 84. Shaft 83 carries an arm 86 arranged exteriorly of metal casing 52 for rotating shaft 83 to contact open position or in the opposite direction, i. e.,

to contact closed position. Arm 86 may be operated by any suitable motor arranged remote from casing 52 and at ground potential by the intermediary of a suitable insulating element. Preferably arm 86 is being attached by means of a linkage including a universal joint to a motor-operated vertical insulating column of the kind of column 8 shown in Figs. 2 and 3.

The push-pull operating mechanism 83, 84, 85, 86 of Figs. 6 and 7 is less involved than that of Fig. 3, and it does not require a slide bearing as the latter does, which features make it more desirable in some respect.

Referring now to Fig. 8, that figure shows a modification of the operating means for the rotary contact-operating insulating column 8 and a modification of column 8 itself, the other parts of the circuit breaker having been omitted, or indicated in a diagrammatic way. Column 8 comprises two superimposed coaxial parts 8a, 8b, which are interconnected by an eccentric element 100. Element 100 is associated with an element 101 and adapted to operate a reciprocating rod 10. Both elements 100 and 101 form a crank mechanism. Rod 10 forms part of a push-pull operating mechanism (not shown in detail) adapted to convert a horizontal operating impulse into a pair of vertical impulses of opposite directions for effecting relative movement of contacts 4 and 5. The crank mechanism formed by elements 100 and 101 permits column 8 to rotate about 360 degrees (without reversing its sense of rotation). Column 8 is supported by shaft 102 resting in two bearings 103. Toothed or spur wheels 104a and 104b are loosely mounted on shaft 102. Toothed racks 105a, 105b are in cooperative engagement with spur wheels 104a and 104b, respectively. Fluid motor 106a comprising piston 107a, cylinder 108a and resetting spring 109a is adapted to operate rack 105a. Fluid motor 106b comprising piston 107b, cylinder 108b and resetting spring 109b is adapted to operate rack 105b. Fluid under pressure may be supplied to motor 106a through solenoid trip valve 110, and cylinder 108a of motor 106a may be vented by means of venting valve 111. Orifice 112a is arranged about midway between the ends of cylinder 108a and adapted to permit cylinder 108b to be supplied with gas under pressure through pipe line 112. Pipe line 112 is controlled by the solenoid reclosing lock-out relay 113. Ratchet gear 114 is fixedly mounted on shaft 102 of column 8 and adapted to be operated either by a ratchet 115a hinged to spur wheel 104a, or by a ratchet 115b, hinged to spur wheel 104b. Racks 105a, 105b, are provided with push rods 116a and 116b, respectively. Push rod 116a controls an interlock limit switch 117 arranged in the energizing circuit of solenoid trip valve 110, while push rod 116b controls venting valve 114 of cylinder 108a.

Alternatively cylinder 108b of fluid motor 106b, may be supplied with gas under pressure through pipe 118 and check valve 119. The rate of escape of gas under pressure from cylinder 108b may be controlled by adjusting needle valve 120.

The control system shown in Fig. 8 operates as follows: Occurrence of a fault as, for instance, an arcing ground connection, causes energization of solenoid trip valve 110 and hence admission of gas under pressure to fluid motor 106a. Piston 107a moving from right to left moves rack 105a from right to left. The latter causes rotation of spur wheel 104a which, in turn, causes a rotation of ratchet wheel 114, shaft 102 and insulating column 8 of approximately 180 degrees, resulting

in separation of contacts 4, 5. Rapid reclosing is effected by gas under pressure flowing through port 112a and pipe 112 in back of piston 107b of fluid motor 106b. This causes piston 107b and rack 105b to move from left to right and ratchet gear 114 to be rotated through ratchet 115b in the same sense as before, thus causing an additional 180 degrees rotation of shaft 102 and column 8 in the same sense as before. Owing to this additional 180 degrees rotation contacts 4, 5 are rapidly reclosed upon separation thereof. Movement of push rod 116b to the right causes opening of venting valve 114 which enables rapid resetting of motor 106a owing to the action of spring 109a. Auxiliary switch 117 which had been opened by push rod 116a is allowed to reclose upon resetting of motor 106a, thus permitting re-energization of solenoid trip valve 110. If the duty cycle of the circuit breaker comprises but one immediate reclosing operation, pipe 112 is blocked upon the first reclosing operation by solenoid lockout valve 113 and this causes column 8 to travel merely to contact open position rather than to move farther to contact closed position.

If contacts 4, 5 are separated as a result of an interrupting operation other than a rapid reclosing duty cycle, contacts 4, 5 are reclosed by admitting gas under pressure to motor 106b through pipe 118 and check valve 119, thus causing piston 107b to move from left to right. Owing to the action of needle valve 120 motor 106b resets itself upon a given period of time. This causes a rotation of spur gear 104b without, however, affecting ratchet gear 114 and column 8.

Although but several embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. In a circuit breaker, the combination of a member at least in part of insulating material defining a passage, a pair of cooperating contacts within said passage, a supply of gas under pressure, means connecting said passage and said supply for producing a blast of gas having a slightly damped pressure wave through said passage, a contact separating means operated independently of the gas pressure in said passage, and means for synchronizing said contact separating means with said blast producing means to separate said contacts when a crest of said pressure wave reaches said contacts.

2. In a circuit breaker, the combination of a member at least in part of insulating material defining a passage, a plurality of serially connected pairs of cooperating contacts within said passage, a supply of gas under pressure, means connecting said passage and said supply for producing a blast of gas having a slightly damped pressure wave through said passage, and a contact separating means operated independently of the gas pressure in said passage for simultaneous separation of all of said pairs of contacts at a time at which said pressure wave reaches the point of break most remote from said source.

3. In a circuit breaker, the combination of a member at least in part of insulating material defining a passage, a plurality of serially connected pairs of cooperating contacts within said passage, a supply of gas under pressure, means

connecting said passage and said supply for producing a blast of gas having a slightly damped pressure wave through said passage, and a contact separating means operated independently of the gas pressure in said passage for simultaneous actuation of all of said pairs of contacts at a time at which a crest of said pressure wave reaches the point of break most remote from said source and irrespective of whether there is a difference in gas pressure at different points of break.

4. In a circuit breaker, the combination of a member at least in part of insulating material defining a passage, a pair of cooperating contacts within said passage, a supply of gas under pressure, means connecting said passage and said supply for producing a blast of gas under pressure having a slightly damped pressure wave through said passage, a contact separating means operating independently of the gas pressure in said passage and comprising an insulating column adapted to be rotated about the longitudinal axis thereof arranged generally parallel to said passage, a transmission interconnecting said column and one of said contacts adapted to convert rotary motions of said column into lineal motions of said one of said contacts in a direction longitudinal of said passage, and a motor for rotating said column, said motor being actuated at a time at which said pressure wave reaches said contacts.

5. In a circuit breaker, the combination of a metal casing, a tubular insulator arranged vertically on and carried by said casing, a supply of gas under pressure, means connecting said casing and said supply for producing a blast of gas under pressure having a slightly damped pressure wave through said casing and said insulator comprising blast entrance means at the end of said insulator adjacent said casing and blast exhaust means at the end of said insulator remote from said casing, a pair of cooperating contacts arranged in the path of said blast, contact separating means operated independently of the gas pressure in said casing and comprising a motor actuated upon a predetermined travel of said pressure wave, an insulating column rotatable about the vertical axis thereof and adapted to be rotated by said motor, and a transmission adapted to convert rotary motions into lineal motions, said transmission interconnecting said column and one of said contacts.

6. In a circuit breaker, the combination of a member at least in part of insulating material defining a passage, a pair of cooperating arcing contacts mounted within said passage for establishing an arc, a supply of gas under pressure, a conduit connecting said passage and said supply for producing a blast of gas having a given pressure wave through said conduit and said passage, a contact separating means operating independently of the gas pressure in said passage and comprising a fluid motor having a pipe connection to said conduit, and means for adjusting the flow of gas through said connection to cause said motor to separate said contacts a predetermined time after the transit of said pressure wave through said conduit past said connection.

7. In a circuit breaker, the combination of a member at least in part of insulating material defining a passage, a pair of cooperating arcing contacts mounted within said passage for establishing an arc, a supply of gas under pressure, a conduit connecting said passage and said supply for producing a blast of gas having a given pressure

wave through said passage, and a contact separating means operating independently of the gas pressure in said passage and comprising a fluid motor arranged at substantially ground potential, said motor having a pipe connection to said conduit whereby said motor is actuated a predetermined period of time after the transit of said pressure wave through said conduit past said connection, an insulating column adapted to be rotated about its axis by said motor, and a transmission interconnecting said column and one of said contacts and adapted to convert rotary motion of said column into lineal motion of one of said contacts.

8. In a circuit breaker, the combination of a metal casing, a tubular insulator immediately adjacent said casing and communicating therewith, a pair of cooperating arcing contacts mounted within said insulator for establishing an arc, a supply of gas under pressure, a conduit connecting said casing and said supply for producing a blast of gas having a given pressure wave through the gap formed between said contacts upon separation thereof, blast exhaust and cooling means at the end of said insulator remote from said casing, and a reciprocatory contact separating means operating independently of the gas pressure in said casing comprising a fluid motor arranged at substantially ground potential, said motor having a pipe connection to said conduit whereby said motor is actuated a predetermined period of time after the transit of said pressure wave through said conduit past said connection, an insulating column adapted to be rotated by said motor about an axis generally parallel to said insulator, and a transmission interconnecting said column and one of said contacts and adapted to convert rotary motion of said column into lineal motion of one of said contacts.

9. In combination, a circuit breaker comprising a plurality of superimposed elements forming a vertical hollow column, said elements including a pair of spaced metal elements each arranged between insulating elements, a plurality of pairs of separable cooperating contacts each associated with one of said insulating elements, means for serially connecting said plurality of pairs of contacts, a supply of gas under pressure, a conduit connecting said hollow column and said supply for producing a blast of gas having a given pressure wave through said hollow column, common means within each metal element for separating pairs of cooperating contacts associated with the insulating elements immediately adjacent thereto, a pair of crank mechanisms exteriorly of said metal elements and insulating elements each operatively associated with one of said common means, and actuating means operating independently of the gas pressure in said hollow column and comprising a first vertical rotary column for insulatingly interconnecting said pair of crank mechanisms, a second vertical rotary column for insulatingly supporting said first rotary column, and a fluid motor arranged at substantially ground potential and actuated in a predetermined relation to the transit of said pressure wave through said hollow column for operating said second rotary column.

10. In a circuit breaker, the combination of a metal casing forming a chamber, a pair of insulators arranged coaxially on opposite sides of said casing and defining tubular extensions of said chamber, a pair of stationary contacts each associated with one of said insulators, a pair of movable contacts each adapted to cooperate with

one of said stationary contacts, guiding means within each of said insulators for telescoping said movable contacts in the direction of the common axis of said insulators, each said guiding means having a supporting flange clamped between said casing and one of said insulators, means for producing blasts of gas under pressure having a predetermined pressure wave through the gaps formed between cooperating contacts upon separation thereof, gas exhaust means on the ends of said insulators remote from said casing, a reciprocatory operating mechanism having a stroke parallel to the axis of said insulators for common simultaneous actuation of said movable contacts in opposite directions, and means for actuating said mechanism including an operator of insulating material and a motor arranged at substantially ground potential for actuating said operator, said motor being adapted to effect synchronized separation of said contacts a predetermined time after said pressure wave reaches said contacts.

11. In a circuit breaker, the combination of a metal casing, a tubular insulator arranged vertically on said casing and communicating therewith, means for producing a blast of gas having a predetermined pressure wave through said insulator, blast exhaust means on the end of said insulator remote from said casing, a pair of cooperating contacts arranged in the path of said blast of gas, an insulating column rotatable about the vertical axis thereof, a transmission for converting rotary motions of said column into vertical lineal motions of one of said contacts, and a pair of sequentially operating fluid motors of the cylinder-piston type adapted to rotate said column sequentially in the same direction about angles of substantially 180 degrees, said first operating motor actuated independently of the gas pressure in said insulator and at a predetermined time after said pressure wave reaches said contacts.

12. In a circuit breaker, the combination of a metal casing, a pair of tubular insulators arranged coaxially at opposite sides of said casing and communicating therewith, means for producing a pair of opposite blasts of gas under pressure each through one of said insulators, gas exhaust means on the ends of said insulators remote from said casing, two pairs of cooperating contacts each arranged in the path of one of said blasts of gas, an insulating column rotatable about the vertical axis thereof, a transmission for converting rotary motions of said column into lineal opposite motions of one contact of one of said pairs of contacts and of one contact of the other said pair of contacts, a shaft for supporting said column, a pair of gears supported on said shaft for rotation independently thereof, a pair of racks each in cooperative engagement with one of said gears, a pair of fluid motors of the cylinder-piston type adapted for alternate operation of said racks, and a ratchet mechanism connecting said gears to said shaft to cause said shaft to be rotated in response to rotation of either of said gears in a common predetermined direction.

GUSTAV E. JANSSON.
